(57) **CLAIM**

The ornamental design for a charger, as shown and described.

DESCRIPTION

FIG. 1 is a perspective view of a charger showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof.

FIG. 8 is another perspective view showing the charger in use; and,

FIG. 9 is a further perspective view thereof showing a cover applied.

The broken line environmental showing is for illustrative purposes only and forms no part of the claimed design.
